UNITED STATES PATENT OFFICE.

WALTER LANE, OF HOLLAND, MICHIGAN, ASSIGNOR TO BUSH & LANE PIANO COMPANY, OF HOLLAND, MICHIGAN.

UPRIGHT PIANO.

Application filed December 29, 1924. Serial No. 758,701.

This invention relates to improvements in upright pianos.

The main object of this invention is to provide an improved upright piano having superior tone quality.

A further object is to provide an upright piano having qualities of a grand piano.

Objects pertaining to details and economies of construction and operation of my improvements will definitely appear from the detailed description to follow.

I accomplish the objects of my invention by the devices and means described in the following specification. The invention is clearly defined and pointed out in the claims.

A structure which is a preferred embodiment of my improvements is clearly illustrated in the accompanying drawing, forming a part of this application, in which:

Fig. I is a front perspective view of portions of the frame of a piano and string plate embodying the features of my invention.

Fig. II is an enlarged detail vertical section on a line corresponding to line 2—2 of Fig. I, the sounding board being shown in operative relation to the string plate, only one string and its coacting hammer being shown.

In the drawing similar numerals of reference indicate similar parts throughout both views.

In practice my present improvements are preferably embodied in a structure having the features shown in my Letters Patent No. 1,146,432, dated July 13, 1915. As the general structure is shown in that patent, I have only illustrated such parts as seem necessary to a complete understanding of my present improvements.

In the accompanying drawing, I only show portions of the frame of a piano, the portions of the frame shown being the bottom member 1 and uprights 2, the back frame not being shown. 3 represents the sounding board.

The string plate 4 is mounted, as is the usual practice, upon a suitable back frame. The wrest plank 5 extends across the top of the frame at the rear of the string plate, the string plate having a rearwardly projecting flange 6 below the wrest plank.

The sounding board is provided with a bridge 7 over which the strings 8 are disposed, the lower ends of the strings being secured to anchoring pins 9. The tuning

pins 10 are passed through the plate webs, designated by the numeral 11.

The tuning pin web 11 has a rearward offset 12 at its lower edge providing a recess 13 below the rest bar 14, the strings 8 being supported by this wrest or pressure bar.

A bridge bar 15 which is, in the structure illustrated, formed as an integral part of the string plate, is disposed in opposed relation to this recess and in coacting relation to the rest bar, that is, its inner edge is disposed so that the strings, when passed over the rest bar 14 and under the bridge bar, are deflected as shown, thereby insuring proper engagement with both.

The hammers 16 are arranged to strike the strings from the bridge bar side thereof. The face 17 of the bridge bar adjacent the hammers is inclined away from the hammers thereby making it possible to mount the hammers so that they strike the strings close to their points of engagement with the bridge bar.

By this arrangement I secure a very clear tone quality, the bridge part being suspended at the ends and being free from wood block and plate webs, with spring pressure on bridge toward the hammers. This, so far as applicant is aware, differs from the usual upright piano construction in which the bridge part is formed as a projection on the web plate with the base of the bridge a part of the web throughout its length, the hammer blow striking wire toward the bridge bearing. Pianos embodying my improvements have very clear tones.

I have illustrated and described my improvements in the particular form which I have followed in practice and I believe the disclosure made will enable those skilled in the art to embody or adapt my improvements as may be desired.

Having thus described my invention, what I claim as new and desire to secure by Letters Patent is:

1. In an upright piano, the combination with a sounding board provided with a bridge, of an upright string plate operatively associated with said sounding board and comprising a tuning pin web having a rearward offset at its lower edge and provided with a string rest at the upper edge of the offset, a bridge bar on said string plate disposed in an opposed relation to said offset of said tuning pin web and adjacent to said

string rest, strings disposed over said string rest and under said bridge bar, the edges of the string rest and bridge bar being disposed so that the strings are held under tension against both and hammers arranged to strike the strings from the bridge bar side thereof, the face of said bridge bar adjacent the hammers being upwardly inclined from its string engaging edge permitting the hammers to 10 the hammers to strike the strings in close proximity to said bridge bar.

2. In an upright piano, the combination with a sounding board provided with a bridge, of an upright string plate operatively associated with said sounding board and comprising a tuning pin web having a rearward offset at its lower edge and provided with a string rest at the upper edge of the offset, a bridge bar on said string plate disposed in an opposed relation to said offset of said tuning pin web and adjacent to said string rest, strings disposed over said string rest and under said bridge bar, the edges of the string rest and bridge bar being disposed so that the strings are held under tension against both and hammers arranged to strike the strings from the bridge bar side thereof.

3. In an upright piano, the combination with a sounding board provided with a bridge, of an upright string plate operatively associated with said sounding board and comprising a tuning pin web recessed at the bottom thereof and provided with a string rest above the recess, a bridge bar on said string plate disposed in an opposed relation to said recess and adjacent to said string rest, strings disposed over said string rest and under said bridge bar, the edges of the string rest and bridge bar being disposed so that the strings are held under tension

against both and hammers arranged to strike the strings from the bridge bar side thereof, the face of said bridge bar adjacent the hammers being inclined from its string engaging edge permitting the hammers to 45 strike the strings in close proximity to said bridge bar.

4. In an upright piano, the combination with a sounding board provided with a bridge, of an upright string plate operatively associated with said sounding board and comprising a tuning pin web recessed at the bottom thereof and provided with a string rest above the recess, a bridge bar on said string plate disposed in an opposed relation to said recess and adjacent to said string rest, strings disposed over said string rest and under said bridge bar, the edges of the string rest and bridge bar being disposed so that the strings are held under tension against both and hammers arranged to strike the strings from the bridge bar side thereof.

5. In an upright piano, the combination with a sounding board provided with a bridge, of an upright string plate operatively associated with said sounding board and comprising a tuning pin web provided with a string rest, a bridge bar on said string plate disposed adjacent to said string rest, strings disposed over said string rest and under said bridge bar, the edges of the string rest and bridge bar being disposed so that the strings are held under tension against both and hammers arranged to strike the strings from the bridge bar side thereof.

In witness whereof I have hereunto set my hand.

WALTER LANE.
